UNITED STATES PATENT OFFICE

156,868

TOY FIGURE CONTAINER FOR GAMES

Jeanette S. Cole, North Kansas City, and
Dora E. Golden, Kansas City, Mo.

Application May 23, 1949, Serial No. 2,826

Term of patent 7 years

(Cl. D58—2)

To all whom it may concern:

Be it known that we, Jeanette S. Cole and Dora E. Golden, both citizens of the United States, residents of North Kansas City, in the county of Clay and State of Missouri, and Kansas City, in the county of Jackson and State of Missouri, respectively, have invented a new, original, and ornamental Design for a Toy Figure Container for Games, of which the following is a specification, reference being had to the accompanying drawing, forming a part thereof.

Fig. 1 is a front perspective view of a toy figure container for games, showing our new design; and,

Fig. 2 is a rear perspective view thereof.

We claim:

The ornamental design for a toy figure container for games, as shown.

JEANETTE S. COLE.
DORA E. GOLDEN.
